UNITED STATES PATENT OFFICE.

JAMES H. WISEMAN, OF CLARKSVILLE, ASSIGNOR OF ONE-HALF TO JOHN F. SMITH, OF SHILOH, TENNESSEE.

CAR-COUPING.

SPECIFICATION forming part of Letters Patent No. 373,040, dated November 8, 1887.

Application filed August 11, 1887. Serial No. 246,696. (No model.)

To all whom it may concern:

Be it known that I, JAMES H. WISEMAN, a citizen of the United States, residing at Clarksville, in the county of Montgomery and State 5 of Tennessee, have invented a new and useful Improvement in Car-Couplings, of which the following is a specification.

My invention relates to an improvement in car-couplings; and it consists in a certain novel 10 construction and arrangement of parts for service, fully set forth hereinafter and specifically pointed out in the claim.

In the drawings, Figure 1 is a longitudinal section of two cars connected by my improved 15 coupling. Fig. 2 is a front view of one of the cars. Fig. 3 is a detail perspective view of the bracket for locking the lever.

Referring by letter to the drawings, A A 20 designate two horizontal parallel bars, provided at the rear ends with the aligned vertical openings; and B designates a sliding bar disposed under the body of the car, in the front end of which is made a vertical opening to align with the openings in the rear ends of the 25 bars A A, and a pivot-bolt, b, is passed through the said aligned openings to pivot the bars A to the sliding bar B. The rear end of the said bar B is reduced to form the stud B', which is passed through a suitable bracket or support 30 under the car; and C represents a spiral spring, which is coiled on the said stud, adapted to yield when the said bars A A are drawn forcibly forward. The ends of the said spring bear, respectively, against the rear side of the bracket 35 or support, through which the stud passes, and a collar, e, on the rear end of the said stud. The front ends of the said bars A A are separated slightly, and provided with the tapered heads D D, having the shoulders d d at the 40 upper and lower sides thereof, at the rear end, and tapered to a point at the front end. e e are aligned vertical openings formed in the said bars A A, near the front end, and through the said openings is passed the bolt E, having 45 a collar, E', on the lower end; and F represents a spiral spring, which is coiled on the said bolt below the lower bar, A, and bearing at the ends against the under side of the said lower bar and the collar on the lower end of 50 the bolt.

It will be seen that when the bars A A are

separated the spring F will be compressed, and the same will have a tendency to draw the said bars together again upon being released. The front ends of the said bars A A are guided laterally by a keeper, G, secured to the under side of the car at the front end, the said keeper being large enough to allow the said bars to be separated vertically to a considerable distance. 55

H designates a lever pivoted to the front end 60 of the car, and connected at the lower end to the front ends of the bars A A by the connecting-link I, so that when the upper end of the said lever is moved laterally the front ends of the bars A A will also be moved laterally. 65 The upper end of the said lever H operates in the transverse slot k in the bracket K, and a leaf-spring, L, is secured on the front side of the lever, adapted to engage automatically in a small notch, k', in the outer end of the said 70 slot k.

The parts of the invention are so arranged that when the upper end of the lever is in the outer end of the slot k (and consequently locked in that position by the spring L being engaged 75 in the notch k') the bars A A are directly under the center of the car-body, and therefore in engaging position.

When two cars approach each other to couple, the tapered heads on the front ends of 80 the coupling-bars A A slide past each other, and the shoulders d d at the rear ends of the said heads engage with each other, and thus form the coupling.

It will be seen that it makes no difference 85 whether the couplings are on the same level or not, and it also makes no difference which of the couplers is above, as the tapered heads will in either case slide past each other and form the engagement described. If the tapered 90 head on one of the couplers passes between the beveled sides of the two tapered heads on the other coupler, the said heads will be separated, as there is not space between them for the head to pass. The said heads are separated against the force of the spring F, and when the shoulders of the said tapered heads pass each other the said spring will cause the heads to approach each other, and thus form 95 the engagement.

When it is desired to uncouple, it is simply necessary to draw one of the pairs of tapered

heads laterally to allow the shoulders thereof to pass from the position in rear of the shoulders of the other heads.

The link I, connecting the front ends of the bars A A with the lower end of the lever H, is double, preferably made of heavy spring-wire, one arm of which is attached to each bar A, and it will be seen that if the said spring is strong enough the spring F may be dispensed with.

A further advantage of this coupling is that, although as long as the cars are on the track the coupling is perfectly secure, the moment that one of the cars leaves the track the couplings at both ends of the said car will be broken—that is, the said car will be uncoupled from the cars in front and rear—thus not endangering the said cars which have not been thrown from the track.

The coupling is, in addition, very simple in construction, and will therefore not be liable

to get out of order, and it will stand a great amount of rough usage without being damaged.

Having thus described my invention, I claim—

The combination of the sliding bar B, supported below the car, the bars A A, pivoted to the front end of the bar B and provided at their outer ends with the arrow-heads D, the bolt E, passed through the bars A A and 30 having the collar E' on its lower end, and a spring, F, coiled around the bolt E and bearing against the collar E' and the under side of the lower bar, A, substantially as specified.

In testimony that I claim the foregoing as my own I have hereto affixed my signature in presence of two witnesses.

JAMES H. WISEMAN.
